UNITED STATES PATENT OFFICE.

JACOB LOEFFELHOLZ, OF NEW YORK, N. Y.

AUTOMOBILIST'S HOOD.

1,068,146.

Specification of Letters Patent. Patented July 22, 1913.

Application filed December 16, 1912. Serial No. 736,894.

To all whom it may concern:

Be it known that I, JACOB LOEFFELHOLZ, a citizen of the United States of America, residing at New York city, borough of Manhattan, county and State of New York, have invented certain new and useful Improvements in Automobilists' Hoods, of which the following is a full, clear, and exact description.

10 This invention relates to an improvement in bonnets or hoods for women automobilists, the object being to provide such a head-piece with a veil or face covering that can be readily slipped over the face and tied, or 15 otherwise secured, around the neck in the manner usually employed by women to fasten veils while riding in windy or cold weather.

One of the chief features of my improvement is that the veil is permanently secured to the bonnet, and when not in use for protecting the face, is, for the most part, hidden from view, the exposed portion of the 20 veil being used, as bonnet strings, to hold 25 the bonnet on the head. A special flap or folder is provided to conceal that portion of the veil which is secured to the bonnet and which is not in use. When not in use to protect the face, the veil has the appearance of 30 bonnet strings.

I will now proceed to describe my invention in detail, the novel features of which I will point out in the appended claims, reference being had to the accompanying drawings, forming part hereof, wherein—

Figure 1 is a perspective view of my improved bonnet, the veil being folded, and adapted for use as bonnet strings; Fig. 2 is a similar view, illustrating the veil in use 40 for protecting the face; Fig. 3 is a perspective view, showing the extensible flap for concealing the veil, the veil being omitted; Fig. 4 is an enlarged cross-sectional detail view of the flap and concealed portion of the 45 veil; and Fig. 5 is a similar view illustrating the point at which the veil is secured to the flap.

My improved bonnet consists of a head-piece 1, a veil 2, and a foldable front-piece 50 or flap 3, which is designed to conceal the veil, or rather a portion of the veil, when said veil is not in use to protect the face, as illustrated in Fig. 2. When not in use to protect the face, the veil can be folded and 55 the greater part of it concealed within the

flap 3 as illustrated in Fig. 1. The flap 3, which is virtually one piece that can be folded, is designed to conceal a portion of the veil, and for the sake of clearness, the said flap 3 is illustrated as consisting of the parts 60 or members 3^a and 3^b which when folded, one over the other, provide a pocket 3^c for the retention of the veil 2. (See Fig. 4.) To hold the members 3^a and 3^b together, when folded, I provide (in this instance) 65 the member 3^a with a socket 6 and the member 3^b with a button 7, which are adapted to engage each other, in the manner of a glove fastener. When the members 3^a and 3^b are secured together the pocket 3^c is 70 formed within which the folded portion of the veil 2 lies, as shown in Fig. 4. The folded flap 3 is secured to the head-piece 1 of the bonnet by means of buttons 4 and sockets 5.

The veil 2 is secured to the foldable flap 3 75 at about the position indicated by 9, Fig. 5. The veil can be secured to the flap by sewing or by pins; in either event the veil is substantially permanently secured to the bonnet and need not be removed, excepting for 80 washing or replacement by another veil, either new or of a different color or thickness.

To use the veil as a protection for the face, as shown in Fig. 2, the flap members 85 3^a and 3^b will be disengaged and separated, after which the veil can be let down, carried around the neck and tied or otherwise secured in place over the face. When the veil has been let down the end sockets and 90 buttons 6 and 7 only will be caused to engage each other to hold the members of the flap 3 together. The intermediate fastening members will be prevented from engagement because of the intervening portion 95 of the veil, this being apparent without illustration. As the folded flap can be secured to the head-piece 1, an extensible member for the front of the bonnet is provided which, if desirable, can be let down over 100 the forehead. The extensibility of the front of the bonnet facilitates the manipulation of the veil, both when folding and unfolding.

From an inspection of the drawings, it will be apparent that when the veil is not in 105 use to protect the face, it is so effectually concealed that its presence can not be detected excepting by close scrutiny. The exposed portions of the veil, will have the appearance of ribbons extending from a 110

- bandeau. Furthermore, the folded veil, especially as it will pass over the head of the wearer, will act to draw the bonnet closely to the head. The member 3^a may be faced 5 with fancy silk or other material which will still further carry out the deception. In practice, the backs of the buttons and sockets will be hidden from view by suitable facings or coverings.
- 10 The flap 3 is normally folded both when concealing the veil and when the veil is down. The members of the flap are disengaged only when the veil is to be let down or folded up. The folded flap is held in 15 engagement with the head-piece when the veil is down and when the veil is folded.
- Having now described my invention, what I claim and desire to secure by Letters Patent is:
- 20 1. The combination, with a lady's hood and a veil attached thereto, of a flap carried by the hood and extending completely around the forward edge thereof and adapted to receive and conceal the folded veil.
- 25 2. The combination, with a lady's hood and a veil attached thereto, of a flap attached to the forward edge of the hood and extending completely around the face portion thereof and adapted to receive the folded veil, the ends of the folded veil extending beyond the hood to form streamers.
- 30 3. The combination, with a lady's hood and a veil attached thereto, of a flap carried by the hood and extending completely around the forward edge thereof and adapted to receive the folded veil, and fastening devices carried by said flap and adapted to

be detachably secured to the body portion of the hood at a plurality of points.

4. In a lady's hood, the combination, of a head covering portion, a flap carried thereby adjacent to its forward edge and subtending substantially the entire extent of such edge, a plurality of spaced detachable fastening members whereby the free edge 45 of said flap may be secured adjacent to the head covering portion of the hood, and a veil secured beneath said flap and adapted when extended to cover the face of the wearer and also adapted when folded to be 50 contained within said flap.

5. In a lady's hood, the combination, of a head covering portion, a band secured thereto adjacent to and parallel with its forward edge, the forward portion of said 55 band being folded rearwardly to form a flap, complementary fastening members carried by the free edge of said flap and the portion of said band adjacent to said head covering portion, and a veil secured to said 60 band between said fastening members and adapted, when extended, to cover the face of the wearer and also adapted, when folded, to be contained beneath said flap, the length of said veil being greater than the length 65 of said band, whereby the ends of the same may protrude beyond said hood to form streamers.

Signed at New York city, N. Y. this 14 day of December, 1912.

JACOB LOEFFELHOLZ.
